(57) CLAIM

The ornamental design for a skin cover for an Xbox one console, as shown and described.

DESCRIPTION

FIG. 1 is a top rear perspective view of a skin cover for an Xbox one console showing my new design; and, FIG. 2 is a top perspective view in use.

The broken lines in FIG. 2 show the Xbox one console and forms no part of the claimed design.

1 Claim, 2 Drawing Sheets

FIG. 1

FIG. 2
